(57) **CLAIM**

The ornamental design for a chocking wheel lock, as shown and described.

DESCRIPTION

FIG. 1 is a reduced scale perspective view of a chocking wheel lock showing my new design, shown in its environmental use;

FIG. 2 is an enlarged scale perspective view thereof;

FIG. 3 is an exploded perspective view thereof;

FIG. 4 is a right side elevational view thereof;

FIG. 5 is a top plan view thereof;

FIG. 6 is a front elevational view thereof;

FIG. 7 is a rear elevational view thereof; and,

FIG. 8 is a bottom plan view thereof.

The broken lines environment is for illustrative purpose only and forms no part of the claimed design.
